UNITED STATES PATENT OFFICE.

JACOB DAVIS, OF FLORIDA, MASSACHUSETTS.

IMPROVEMENT IN WASH-BOILERS.

Specification forming part of Letters Patent No. **131,212**, dated September 10, 1872.

Specification describing a new and useful Improvement in Clothes-Washer, invented by JACOB DAVIS, of Florida, in the county of Berkshire and State of Massachusetts.

Figure 1 is a vertical longitudinal section of my improved washer. Fig. 2 is a horizontal section of the same taken through the line *x x* Fig. 1.

Similar letters of reference indicate corresponding parts.

My invention has for its object to furnish an improved washer for washing cloth, clothes, bedding, &c., quickly and thoroughly, without wearing the cloth, straining the seams, or injuring them in any way; and it consists in the device, constructed as hereinafter more fully described, to adapt it to be applied to an ordinary wash-boiler.

A represents an ordinary oblong or oval boiler. *B* is a false bottom, so formed as to fit into the boiler *A*, and which is supported at a little distance above the bottom of the boiler *A* by flanges *C* attached to its side edges, the lower edges of which flanges rest upon the bottom of the boiler *A*. At the ends of the boiler *A* portions *c'* of the flanges *C* extend up nearly to the top of the boiler *A*. The false bottom *B* inclines upward slightly from its center toward each end, and its ends are cut off before quite reaching the upwardly-projecting portions *c'* of the flanges *C*. *D* are plates, the lower edges of which are attached to the end edges of the false bottom *B*, and the side edges of which are attached to the side edges of the upwardly-projecting portions *c'* of the flanges *C*. The plates *D* incline outward as they extend upward, and their upper end edges are secured to the upper end edges of the upwardly-projecting portions *c'* of the flanges *C*; or are connected with said end edges by a cap-plate. In the plates *D*, at or near their upper ends, is formed a series of small holes, *d'*, as shown in Figs. 1 and 2. In the central part of the false bottom *B* is formed a transverse slot, *b'*, which is covered to prevent the clothes from getting into it and thus interfering with the proper operation of the washer, by a plate, *E*, a little wider than the slot *b'*, and the ends of which are bent down-

ward, and are secured to the side parts of the said false bottom *B*. The plate *E* is supported by a plate, *F*, the upper edge of which is attached to the middle part of the plate *E*. The plate *F* projects down through the center of the slot *b'* of the false bottom *B*, so that its lower edge may rest upon the bottom of the boiler *A*. The end parts of the plate *F* project beneath the side parts of the false bottom *B* to the flanges *C*, to which they are attached; or said side parts may rest upon the true bottom. The plate *F* thus divides the space beneath the false bottom *B* into two compartments. By this construction two flues, *G*, are formed, gradually increasing in depth towards the ends of the boiler, and gradually decreasing towards the top of the boiler. The flues *G* communicate with the interior of the boiler at one end through the slot *b'* in the false bottom *B*, and at their other ends through the holes *d'* in the upper parts of the plates *D*.

Heat may be applied to the washer by placing the boiler *A* upon a stove, range, furnace, or other heater, or by introducing steam from a steam-generator through a pipe. By this construction, as the heat is applied, the boiling suds and steam pass up through the flues *G*, and are discharged through the holes *d'* upon the clothes in the interior of the boiler, through which they pass to the slot *b'*, and back into the flues *G*, thus keeping up a continuous circulation, cleaning the clothes thoroughly in a very short time.

In the case of round or square boilers the circulation may be established through a single tube, passing up through the center of the boiler.

Having thus described my invention, I claim as new and desire to secure by Letters Patent—

A bottom, *B*, having slot *b'*, raised cover *E*, and plates *D* with perforations *d'* at the top only, applied in combination with a clothes-boiler, as and for the purpose described.

JACOB DAVIS.
